UNITED STATES PATENT OFFICE.

KATE LOCKWOOD NEVINS, OF RANCHO HERMOSA, CONTRA COSTA COUNTY, CALIFORNIA.

DESIGN FOR A PITCHER.

SPECIFICATION forming part of Design No. 32,810, dated June 12, 1900.

Application filed December 14, 1897. Serial No. 661,914. Term of patent 14 years.

To all whom it may concern:

Be it known that I, KATE LOCKWOOD NEVINS, a citizen of the United States, residing at Rancho Hermosa, in the county of Contra Costa, State of California, have invented and produced a new and original Design for a Pitcher, of which the following is a specification, reference being had to the accompanying drawings, forming a part thereof.

The leading or material feature of my design resides in the cover 2 and the adjacent portion 1 of the pitcher, which are configured to resemble the harness and trappings of a domesticated elephant.

3 represents the hinge, which has claw-like extensions 4.

5 represents the straps of the harness, joined by a ring 6 and buckle 7, and the end of one of the straps is turned up, as shown at 8.

I claim—

The design for a pitcher as herein shown and described.

K. LOCKWOOD NEVINS.
